CASE II.

To all whom it may concern:

Be it known that I, EMIL CRISAND, of New Haven, in the county of New Haven and State of Connecticut, have invented a new Design for Embroidery-Pattern; and I do hereby declare the following, when taken in connection with the accompanying drawings and the letters of reference marked thereon, to be a full, clear, and exact description of the same, and which said drawings constitute part of this specification, and represent the design.

This invention relates to a design for embroidery-pattern, intended especially for perforated board; and it consists in the peculiar configuration and ornamentation of the motto, as shown in the accompanying illustration.

The motto forming the base of this design is "Give Us this Day Our Daily Bread," the first

The ornamentation in this design consists of a border of scroll-work around the motto, running into and interlacing with the letters, as shown in the accompanying illustration.

I claim—
